(57) **CLAIM**

The ornamental design for a motor assembly, as shown and described.

DESCRIPTION

FIG. 1 is a front perspective view of a motor assembly according to a first embodiment of our design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a front perspective view of a motor assembly according to a second embodiment of our design;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

FIGS. 1–7 include general shading which should not construe any particular material or surface property. The application of shading, stippling, and/or line thicknesses shown in FIGS. 8–14 is used to disclose contrast in materials and/or surfaces.
